United States Patent Office

Des. 185,917

Patented Aug. 18, 1959

185,917

TABLE LAMP OR SIMILAR ARTICLE

William J. Carpenter, Burbank, Calif.

Application March 3, 1958, Serial No. 49,872

Term of patent 14 years

(Cl. D48—20)

Fig. 1.

Fig. 3.

Fig. 4.

Fig. 2.

Figure 4 is a rear elevational view thereof with the shade and bulb omitted for convenience of illustration.

The dominant features of my design reside in the portions shown in full lines.

I claim:

The ornamental design for a table lamp or similar article, as shown and described.
